UNITED STATES PATENT OFFICE.

WILLIAM C. KING, OF PITTSBURG, PENNSYLVANIA.

DESIGN FOR A TUMBLER, &c.

SPECIFICATION forming part of Design No. 19,162, dated June 18, 1889.

Application filed March 11, 1889. Serial No. 302,904. Term of patent 7 years.

To all whom it may concern:

Be it known that I, WILLIAM C. KING, a citizen of the United States, residing at Pittsburgh, in the county of Allegheny and State of Pennsylvania, have invented and produced a certain new and original Design for Tumblers, Jelly-Glasses, &c., of which the following is a specification.

The invention described herein relates to a certain new and original design for tumblers, jelly-glasses, and other analogous articles of glassware.

In the accompanying drawings, forming a part of this specification, Figure 1 is a view in elevation of a tumbler embodying my design, and Fig. 2 is a top plan view of the same.

The lower portion 1 of the glass flares outwardly from the lower end toward the top of

the vessel. The leading or characteristic feature of my design consists in the upper portion 2, relatively larger than the widest part of the tapering lower portion, having its wall forming an angle with the wall of the lower portion, a shoulder 3 being located in the plane of the adjacent ends of the upper portion 1 and lower portion 2.

I claim herein—

The design for a tumbler, jelly-glass, &c., as herein shown and described.

In testimony whereof I have hereunto set my hand.

WILLIAM C. KING.

Witnesses:

DARWIN S. WOLCOTT,
R. H. WHITTLESEY.
